UNITED STATES PATENT OFFICE.

THOMAS A. BRIGGS, OF PROVIDENCE, RHODE ISLAND, ASSIGNOR TO BOSTON WIRE STITCHER COMPANY, OF PORTLAND, MAINE, A CORPORATION OF MAINE.

METHOD OF PACKAGING WIRE STAPLES AND THE PACKAGE PRODUCED THEREBY.

Application filed December 14, 1922. Serial No. 606,858.

To all whom it may concern:

Be it known that I, THOMAS A. BRIGGS, a citizen of the United States, residing at Providence, in the county of Providence, State of Rhode Island, have invented certain new and useful Improvements in Methods of Packaging Wire Staples and the Packages Produced Thereby, of which the following is a specification.

10 This invention relates to an improved method of packaging wire staples and to the package for the same.

One object of the invention is to provide a method of putting up wire staples in mercantable packages whereby they may be conveniently handled and transported in compact form for supplying refills to hand stapling machines, employed as office or desk appliances, and also to other types of 20 machines used in various manufacturing arts.

Another object of the invention is to provide a flexible strip-like holder for the staples which may be wound into a roll of compact form to be packed within a minimum space for shipment.

Another object of the invention is to provide a rolled strip of staples which may be used as a supply charge for the machine to 30 adapt the staples to be delivered individually therefrom as required by the stapling operation.

Another object of the invention is to provide for holding the staples in alined relation on the strip in correct position for delivery one at a time to the stapling-mechanism without danger of their becoming misaligned or getting loose to jam or clog the machine.

40 Another object of the invention is to provide a carrying-strip or holder for the staples which may be constructed from fiber or paper stock to render it so inexpensive that it may be discarded or thrown away after 45 the staples have been stripped therefrom.

Another object of the invention is to provide a holder or container to which the staples may be applied during the process of their manufacture.

50 Another object of the invention is to provide a holder or container for the staples which may be constructed from strip material fed into the staple-forming machine, so that both the holder and its staples are manufactured at the same time and delivered as

a complete package with the staples assembled in place on the holder.

Further objects of the improvement are set forth in the following specification which describes a preferred embodiment of 60 the invention as illustrated by the accompanying drawings. In the drawings:

Fig. 1 is a view in perspective of a length of the rolled staple-strip or holder showing the staples assembled thereon;

Fig. 2, a slightly enlarged view showing a short section of the strip with a portion of its folded side torn away to illustrate the manner in which the staples are held in place by an inner core extending between 70 their overlying legs;

Fig. 3, a perspective view of a section of the inner core of the strip;

Fig. 4, a similar view of the overlying cover-strip or wrapper for the core;

Fig. 5, a cross-sectional view of the staple-holder showing the manner in which the wrapper-strip is folded around the inner core with the staples straddling the latter to hold them in alinement; and

Fig. 6, a perspective view of one of the staples which the package is designed to contain.

My improved package is designed for holding a large number of separate wire 85 staples as distinguished from the type of flat staples which are constructed from sheet metal and joined together in a continuous length. Staples of the present type are formed from wire cut into short lengths 90 and bent into inverted U-shape, see Fig. 6 of the drawings, and are used for stapling together sheets of paper, fastening tags and tickets to articles, closing envelopes and for sundry other purposes. Various types of 95 stapling machines are employed for inserting the staples through the work and bending and clinching their legs thereagainst, and reference is had to U. S. Letters Patent

No. 836,662, dated November 20, 1906; No. 850,290, dated April 16, 1907; No. 1,119,093, dated December 1, 1914; and U. S. patent application Serial No. 567,803, filed June 10, 1922, as illustrative thereof. In some types of wire-stitching machines the staples are 105 formed in the machine from a continuous length of wire fed thereto; but with hand staplers and foot-power machines it is the more common practice to supply the staples in commercial packages from which 110

they may be delivered to the stapling-mechanism of the machine.

Heretofore it has been the usual method to package the staples on a wooden "stick", 5 or on a hollow metal core of rectangular shape in cross-section, but this is a wasteful practice as the wooden and metal "sticks" are costly to manufacture, besides being cumbersome and bulky and adding to 10 the size and weight of the package.

It is therefore the object of the present invention to provide a holder or container for the staples which will be less bulky in size, lighter in weight, and much less expensive to manufacture. To this end I 15 have devised a holder or container which may be constructed from stiff paper, fiber or similar inexpensive stock, and which may be rolled or doubled on itself to compact the 20 assembled staples into a minimum of space, while being capable of presenting them to the stapling machine in position to be properly delivered to the stapling-mechanism thereof.

25 Referring to the drawings, my improved staple holder or package consists essentially of a composite strip 2 of flexible material on which the staples are assembled in parallel alinement with their legs in overlapping relation. The strip 2 comprises two 30 connected parts, an inner flat core 3, shown in Fig. 3, and an outer cover or wrapper 4, see Fig. 4, having its marginal portions 5 folded down around the edges of the core 3 in the manner as illustrated in Figs. 2 and 5.

The core 3 is constructed from somewhat 35 heavier stock than the cover or wrapper strip 4, and any suitable inexpensive material may be used for the purpose such as 40 heavy cardboard, straw-board, rag or jute fiber or the like. The overlying wrapper strip 4 is made from somewhat thinner material, such as strong, tough paper, or I may 45 employ a fibrous material such as jute tag 50 stock or the like.

The staples 8, shown in detail in Fig. 6, 55 are assembled on the strip or holder 2 by piercing their legs through the outer marginal portions of the wrapper 4 so that 60 they straddle the underlying core 3. The preferred method of applying the staples to 65 the strip 2 is by feeding the latter through the machine in which the staples are manufactured so that as each staple is formed it 70 may be inserted in the wrapper 4 by piercing or punching its legs therethrough. The successively formed staples 8 are pierced 75 through the wrapper 4 with their cross-bars lying in parallel relation at a slight distance 80 apart to leave sufficient stock to insure that the legs of the staples will not tear away 85 the paper or other material of the strip. It will be understood, of course, that the 90 staples 8 are inserted through the upper 95 strip or wrapper 4 before the marginal por-

tions of the latter are folded around the underlying core 3, the purpose of the core or bottom strip 3 being to maintain the staples in alinement.

After the staples have been pierced 100 through the strip in the manner as above explained they are collapsed or nested as shown most clearly in Fig. 2 to bring their legs into overlapped relation with each other. The under strip or core 3 is preferably of a width to adapt its marginal edges 105 6 to press slightly against the straddled legs of the staples to frictionally grip the latter to hold them from dislodgment, and the overhanging portions 5 of the upper strip or wrapper 4 are folded around the under side of the core at 8, see Figs. 2 and 5, to further bind and secure the staples in place. In some cases, however, the core 3 might be 110 dispensed with and the staples carried solely by the folded wrapper 4.

I have found that by employing a sufficiently stiff material for the wrapper or holding strip 4 its folded portions 8 may 115 be pressed or creased into place so that there will be no tendency for them to unfold or become loose from the edges of the core 3. If desired, however, the overlapped portions 8 of the wrapper 4 might be pasted, glued, 120 stitched or otherwise permanently fastened 125 to the core 3 to render the union more secure.

The folding and creasing of the wrapper-strip 4 around the edges of the core 3 may 130 be accomplished by feeding the whole strip through suitable dies or rollers after the staples have been applied thereto by piercing their legs through the wrapper, it being understood that the staples 3 are collapsed on the core 3 previous to the folding operation through the application of pressure on their legs. All of these several operations of forming the staples; piercing their legs through the wrapper-strip 4; collapsing them into nested relation on the core 3; and 135 folding and creasing the marginal portions of the wrapper around the edges of the core may be performed in close sequence as the two parts of the staple holder or strip 2 are fed through the staple-manufacturing machine.

After the staples have been assembled on, and bound to, the strip or holder 2 in the manner as described the strip may be doubled or rolled on itself as illustrated in 140 Fig. 1, to produce a more compact package. The stock from which the wrapper 4 and core 3 are constructed is chosen for pliability to allow for rolling the strip, but in some cases I have found it of advantage to 145 slightly score or crimp the under side of the core 3 as shown at 9 in Fig. 3 to further enhance its flexibility and guard against splitting or rupturing the stock.

150 It will be observed from the foregoing

that my invention provides a particularly neat and attractive method of packaging wire staples in commercial form for convenient handling, packing and shipping.

5 Moreover, the improved package is of minimum bulk and weight and is adapted to compact a large number of staples within a minimum space while holding them in proper relation for delivery to the stapling mechanism of the machine in which they are used.

10 My improved package will accommodate five thousand or more staples in a roll of a few inches in diameter, and such a roll or strip may be used as a charge for the stapling machine in much the same manner as an ammunition belt is employed in automatic or rapid-fire machine guns. The individual staples are securely held in aligned relation 15 on the strip or package without danger of their breaking loose or becoming misaligned and misplaced to clog or choke the machine.

15 In addition my improved holder for the staples is most economical to manufacture, and being of minimum weight and bulk and foldable on itself it lends itself to more compact grouping in packing or boxing for shipment.

20 It is to be understood that while I have shown and described a preferred embodiment of the invention, the same is susceptible of various modifications without departing from its spirit or scope as expressed in the appended claims. Therefore, without limiting myself herein strictly as to form, arrangement and material, I claim:

- 25 1. An improved package for wire staples consisting in a composite holder comprising a substantially flat band-like core, and a strip of flexible material overlying the core with the staples arranged in parallel relation therewith and having their legs pierced therethrough to straddle the edges of the core.
- 30 2. An improved package for wire staples consisting in a composite strip comprising a substantially flat band-like core, and a wrapper of flexible material overlying the core with its marginal portions folded around the edges thereof, the staples being arranged

across the width of the strip with their legs pierced through the wrapper and nested in overlapped contiguous relation along the edges of the core.

3. An improved package for wire staples 55 consisting in a band-like core, and a covering strip or ribbon of flexible material overlying its top and folded around its edges and having the staples arranged cross-wise thereof with their legs pierced through 60 the strip and nested in overlapped relation on the core to adapt the strip to be rolled or doubled on itself to compact the whole within a minimum space.

4. As a new article of commerce a continuous staple-carrying tape consisting in a flexible strip of material having the staples placed in parallel relation thereacross with their legs pierced through the marginal portions thereof and nested in overlapped relation therewith along with the edges of the strip 65 folded back to enclose the same.

5. A new article of commerce consisting in a staple-carrying tape comprising a strip of flexible material having the staples placed 75 thereacross in parallel contiguous arrangement with their legs pierced therethrough and nested in overlapped relation and the marginal portions of the strip folded therewith.

6. An improved method of packaging wire staples consisting in arranging them in parallel relation with their legs straddled across a band-like strip and nested to overlap one another therewith, and placing a 80 flexible wrapper across the top of the strip and folding its marginal portions around the edges thereof to enclose the legs of the staples.

7. An improved method of packaging wire staples consisting in arranging them in parallel relation across a strip of flexible material with their legs pierced therethrough and nested in overlying relation therewith, and folding the marginal sides of the strip 85 across the legs of the staples to hold them in place.

In testimony whereof I affix my signature.

THOMAS A. BRIGGS.
